tion of Maine

No Drawing. Application February 18, 1939,
Serial No. 257,102

11 Claims. (Cl. 196—10)

This invention relates to improvements in the catalytic condensation of low boiling hydrocarbons to produce normally liquid hydrocarbons of gasoline boiling range.

5 The low boiling hydrocarbons to which we refer more particularly are those saturated, or paraffin, and unsaturated, or olefin, hydrocarbons containing five and less carbon atoms per molecule, methane, ethane, ethylene, propane, 10 propylene, normal butane, isobutane, normal butylene, isobutylene, pentanes and pentenes. These hydrocarbons may be designated the C₁, C₂, C₃, C₄, and C₅ compounds, or collectively the C₅— compounds. Of these low boiling hydro- 15 carbons the C₁, C₂, C₃ and C₄ compounds, or collectively the C₄— compounds, are normally gaseous hydrocarbons, whereas the C₅ com- 20 pounds are normally liquid hydrocarbons. The higher boiling hydrocarbons to which we refer 25 are those containing six or more carbon atoms per molecule within the boiling range of gaso- line and may be designated the C₆— compounds.

The term "catalytic condensation" as applied to such hydrocarbons includes polymeriza- 30 tion of unsaturates and alkylation or reaction 35 between saturates and unsaturates. Catalytic polymerization of unsaturates has been proposed, and practiced, as a method of recovering motor fuel gasoline of special value from less valuable hydrocarbon gas mixtures containing sufficient unsaturated components. Gas mixtures so pro- 40 cessed have included gas mixtures from cracking operations containing as produced sufficient unsaturated components and gas mixtures pre- 45 liminarily processed, catalytically or thermally, to produce sufficient unsaturated components by decomposition of saturated components. While some of these previous proposals and practices have involved incidental alkylation, the condi- 50 tions of operation have tended to suppress alkylation rather than to promote this type of reaction. Alkylation and polymerization are, in some respects, inconsistent reactions, and consequently it is not unnatural that those seeking 55 to effect condensation by polymerization should have avoided conditions promoting alkylation.

We have discovered that, by appropriate cor- 60 relation of charging stock, temperature, pressure and catalyst, we can effect condensation with substantial alkylation, either with concurrent polymerization or to the substantial exclusion of polymerization. By means of this correlation the process of our invention effects catalytic condensation of mixtures of low boiling hydro- 65 carbons including saturates and unsaturates to

produce gasoline-like hydrocarbon products, su- 70 perior in important respects to those of poly- merization processes, in which alkylation if oc- 75 ccurring at all is merely incidental, with sev- eral important process advantages.

In carrying out the process of our invention, we use a charging stock which comprises a mix- 80 ture of low boiling hydrocarbons consisting pre- 85 dominantly of C₄— hydrocarbons and contain- 90 ing a substantial portion of C₅ hydrocarbons, the C₄— hydrocarbons containing not less than about 40 mol percent. of ethane, propane and butanes, advantageously not less than about 15, of better 10 mol percent. of ethane and propane and not more than about 25, or better 22, mol percent. 15 of normal butylene and isobutylene on its total content of C₄— hydrocarbons. The C₅ hydrocar- 20 bons in the charging stock comprise pentanes and pentenes and should be present in the mix- 25 ture in an amount not less than about 20 mol percent. on the total content of C₅— hydrocar- 30 bons. We pass this charging stock in contact 35 with a phosphoric acid catalyst at a tempera- 40 ture of about 200°—450° F., or better about 200° to 360° F., under a pressure upwards of about 45 500 lbs. per square inch, or better upwards of about 700 lbs. per square inch, whereby we effect 55 substantial condensation of saturates and un- 60 saturates, that is we effect substantial con- 65 densation by alkylation. The ethylene, propylene 70 and butylene content of the low boiling hydro- 75 carbons subjected to the catalyst contact is with 80 advantage limited to about 40, or better 35 mol percent., on the total content of C₄— hydrocar- 85 bons. The ethane content of this mixture of 90 low boiling hydrocarbons is with advantage con- 95 trolled so it is not less than about 2 mol percent. 100 on the total content of C₄— hydrocarbons.

In our process, using a phosphoric acid cata- 105 lyst, correlation of charging stock composition, 110 temperature and pressure are important, but of 115 these three factors correlation of charging stock 120 composition and temperature appear to be more 125 important, or at least more critical, than the 130 pressure. As previously noted, alkylation re- 135 actions and polymerization reactions are in- 140 consistent in some respects. In particular, ole- 145 fins may react either with olefins or with paraf- 150 fins, whereas the paraffins react only with ole- 155 fins. Consequently, with a charging stock of 160 given composition, olefins become less available 165 for reaction with paraffins to the extent that 170 they react with each other. In carrying out our 175 process, polymerization is suppressed at least 180

to the extent to which it interferes with substantial alkylation.

We have observed that the paraffins are apparently more reactive with respect to alkylation as they decrease in molecular size. Specifically, we have found that propane is more reactive with respect to alkylation than are the butanes and pentanes and that ethane is in turn more reactive than propane. The olefins, on the other hand, appear to be more reactive with respect to polymerization as their molecular size increases at least within the range of normally gaseous hydrocarbons. We have also found that lower temperatures tend to promote alkylation and suppress polymerization whereas higher temperatures, at least within the range in which alkylation might otherwise be effected, tend to promote polymerization and to suppress alkylation. In our process the composition of the charging stock and the temperature of catalyst contact are further interrelated in that, with any given temperature, alkylation can also be promoted by lowering the concentration of olefins in the gas mixture, by lowering the concentration of olefins more reactive with respect to polymerization in the low boiling hydrocarbon mixture or by increasing the concentration of paraffins more reactive with respect to alkylation in the gas mixture. We have now discovered that the presence of C₅ hydrocarbons increases the conversion of the C₄- paraffins with a resulting increase in the yield of condensed hydrocarbons of gasoline boiling range. The use of a charging stock containing a substantial proportion of C₅ hydrocarbons is of further advantage in that the alkylation of such a charging stock utilizes those C₅ hydrocarbons which heretofore have not been amenable to recovery in the production of gasoline. The presence of C₅ hydrocarbons in a charging stock subjected to the usual polymerization processes is highly undesirable because these C₅ hydrocarbons are a source of overpolymerization with the result that the end point of the polymerized product is too high and the life of the catalyst is materially shortened. By using a substantial amount of C₅ hydrocarbons in a charging stock for our alkylation process the C₅ hydrocarbons are materially condensed into a useful product and not only increase the yield from the C₄- hydrocarbons but also improve the physical characteristics of the resulting gasoline-like condensation product as hereinafter more fully described.

In the process of our invention, these several factors are correlated as follows: The temperature of catalyst contact is limited to a range within which substantial alkylation can be effected. At temperatures above about 330° to 360° F. consumption of olefins in polymerization begins to interfere with the alkylation reaction particularly if the gas mixture includes a substantial content of olefins more reactive with respect to polymerization. Temperatures above about 450° F. do not appear to be useful if substantial alkylation is to be effected. At temperatures below about 200° F., difficulties are encountered with respect to control of moisture content of the catalyst, softening of the catalyst and the stripping of condensation products from the catalyst. The composition of the charging stock is controlled, with respect to the temperature of catalyst contact and the pressure, to promote alkylation and to limit polymerization impeding effective alkylation. The charging stock composition is controlled to

include a substantial proportion but not more than about 25 mol percent. of C₅ hydrocarbons on its total content of C₅- hydrocarbons. The charging stock composition is also controlled to include not less than about 40 mol percent. of ethane, propane and butanes on its total content of C₄- hydrocarbons and, with advantage, to contain not less than about 15, or 20, mol percent. of paraffins more reactive with respect to alkylation, ethane and propane, on its total content of C₄- hydrocarbons, and with advantage not less than about 2 mol percent. of ethane, particularly reactive with respect to alkylation, on its total content of C₄- hydrocarbons. The charging stock composition is controlled to include a substantial proportion but not more than about 22 or 25 mol percent. of olefins more reactive with respect to polymerization, the butylenes, on its total content of C₄- hydrocarbons and, with advantage, a substantial proportion but not more than about 35 or 40 mol percent. of ethylene, propylene and butylenes on its total content of C₄- hydrocarbons. Pressures upwards of 500 lbs. per square inch are useful in our process. In this range, somewhat higher pressures appear to be more useful than the lower pressures. Such higher pressures, upwards of about 700 lbs. per square inch for example, may assist in suppressing polymerization and promoting alkylation.

The period of catalyst contact is not critical. It must be sufficient to effect the desired reactions, but it appears to have little if any part in the distribution of olefin consumption between polymerization reactions and alkylation reactions. Prolonged periods of catalyst contact may involve some alkylation of condensation products originally produced by polymerization. Within the region of catalyst contact, the hydrocarbons present may exist in liquid phase, in vapor phase or in a mixture of liquid and vapor phases. The relatively low temperatures and the relatively high pressures used in our process tend towards the maintenance of at least some liquid material within the region of catalyst contact, and some incidental advantages flow from this circumstance to the extent that such liquid phase conditions exist.

We use the known phosphoric acid condensation catalysts in carrying out our process. An appropriate phosphoric acid catalyst may be prepared, for example, by mixing orthophosphoric acid or pyrophosphoric acid with an appropriate carrier, siliceous materials such as kieselguhr or an aluminum silicate for example, and calcining the mixture at a temperature of 350° to 750° F. The calcined catalyst may comprise three parts by weight of the phosphoric acid compound and one part by weight of the carrier, for example. The calcined mixture may be ground and sized or pelleted or some carbonaceous material may be incorporated into the mixture prior to calcination to render the calcination product porous.

Special apparatus for carrying out the process of our invention is not necessary. The catalyst contact chamber may be of any conventional design appropriate to effect thorough contact between the catalyst arranged within the chamber and the charge passed therethrough and may be provided with any conventional means for maintenance and control of the proper temperature conditions therein. As a matter of catalyst economy, the charge is with ad-

vantage preheated to the reaction temperature prior to its introduction into the catalyst chamber. Heat exchange between the charge and materials flowing through other parts of the system may be utilized in such preheating as may expedient in any particular system. Conventional recovery and fractionation equipment may be used to collect and separate the liquid hydrocarbon product of gasoline boiling range.

The following example embodying specific operations in accordance with our invention will illustrate the advantages offered by alkylation of a hydrocarbon mixture containing a substantial proportion of C_5 hydrocarbons as compared with a product obtained from a similar charging stock treated by the customary low pressure polymerization operation. The alkylation was effected by passing the charging stock through two catalyst towers in series, the temperature of the two towers being 300° and 400° F., respectively, the gauge pressure being 800 lbs. per square inch in both towers, and the feed rate being 0.64 and 0.96 gallon per hour per pound of catalyst in the first and second towers, respectively. The charging stock, comprising a debutanizer liquid overhead, for the alkylation and polymerization operations was the same and had the following composition:

30	Feed stock		
C_6H_6 mol. percent	liq. percent	0.8	0.5
C_2H_4 mol. percent	liq. percent	0.2	0.1
C_3H_8 mol. percent	liq. percent	1.6	1.3
C_4H_8 mol. percent	liq. percent	11.3	9.6
C_5H_8 mol. percent	liq. percent	16.1	14.9
C_6H_{10} mol. percent	liq. percent	25.8	23.7
C_7H_{10} mol. percent	liq. percent	22.9	25.0
C_8 mol. percent	liq. percent	21.3	24.9

The products obtained by alkylation and by polymerization were stabilized to C_{6+} and had the following characteristics:

45	Alkylation	Polymerization
Gravity, API 60° F.	58.7	52.6
Initial point, °F.	158	130
End point, °F.	467	512
Percent distilled at 302° F.	93.0	87.0

The foregoing comparison demonstrates the improved results which may be obtained by alkylation of a hydrocarbon mixture containing a substantial portion of C_5 hydrocarbons and shows the minimized tendency toward overpolymerization in the case of alkylation as compared with polymerization. This minimized tendency toward overpolymerization is largely due to the low temperatures which may be used in the alkylation of low boiling hydrocarbons. Furthermore, the low operating temperature in the alkylation process prevents or at least minimizes local high temperature zones on the surface of the catalyst because of the liquid phase operation resulting from the temperature and pressure conditions employed in the alkylation process. The presence of C_5 hydrocarbons in the charging stock aids in the maintenance of a liquid phase in the catalyst towers. The heat of polymerization is more rapidly dissipated from the catalyst surface during alkylation than during polymerization by virtue of the fact that heat transfer is more efficient in a liquid medium, occurring during alkylation, than in a gaseous medium, occurring during polymerization. The cooling effected by vaporization of liquid at the catalyst surface further

minimizes the formation of local high temperature zones in the catalyst. The low temperature thus maintained in the catalyst bed materially lengthens the life of the catalyst to a value several times as great as the catalyst life for polymerization processes.

The product obtained by alkylation of low boiling hydrocarbons containing a substantial amount of C_5 hydrocarbons is further characterized by higher yields, higher octane value and higher lead susceptibility than a product obtained by polymerization of similar charging stock. Thus a yield increase of 8.5% of gasoline, having a Reid vapor pressure of 9 lbs., is obtained by alkylation of a charging stock comprising C_5 - hydrocarbons at 300°-400° F. and 800 lbs. pressure as compared to a 3.4% yield increase obtained by low pressure polymerization of a charging stock comprising C_4 - hydrocarbons at 380°-500° F. and 160 lbs. pressure, these increases being measured as a yield of such gasoline over and above that obtained directly from a cracking plant without condensation of the C_5 - hydrocarbons. An increase of 0.5 in the octane number of the gasoline-like condensation product is produced by alkylation of the C_5 - hydrocarbons over the octane number of the product obtained by polymerization of C_4 - hydrocarbons. This increase in the octane number of the gasoline is apparently due to the conversion of C_5 hydrocarbons having an octane blending value of 80 to 90 into gasoline-like hydrocarbons having an octane blending value of 90 to 100. By "octane value" we refer to the octane number determined by the Cooperative fuel research motor method. By "blending value" we refer to the apparent octane value of the product in blends with other gasolines of known lower octane value. The lead susceptibility of the gasoline obtained by alkylation of C_5 - hydrocarbons is 8.6, whereas that obtained by polymerization of C_4 - hydrocarbons is only 7.4. The gasoline from untreated distillates has a still lower lead susceptibility of 6.6. This higher lead susceptibility obtained in accordance with our invention appears to be due to the production of more paraffinic gasoline by alkylation and to the removal of unsaturated C_5 hydrocarbons, paraffinic hydrocarbons having greater lead susceptibilities than olefinic hydrocarbons.

By "lead susceptibility" we refer to the octane number rise per cc. of tetra-ethyl-lead added to a gallon of gasoline at a concentration of 0.5 cc. of tetra-ethyl-lead per gallon of gasoline. Alkylation of the C_5 - hydrocarbons has a still further advantage over low pressure polymerization in that the refinery vapor pressure balance is lowered due to the removal of C_5 hydrocarbons thereby permitting the use of greater quantities of natural or casinghead gasoline in the refinery distillate.

One advantage of our process is improved yield. Our invention makes possible the recovery of yields substantially larger than could be had from polymerization of unsaturates to the substantial exclusion of alkylation. Our invention enables the recovery of yields deriving as much as 15% to 45% or more from saturates. Another advantage of our process resides in the fact that it makes available, for the production of liquid gasoline-like products, hydrocarbon materials which hitherto either could not be so used at all or could not be so used economically. Our process derives special advantage from the fact that ethane and propane, particularly, are thus recoverable as liquid gasoline-like products.

Butane and pentane, for example, can be dehydrogenated and the resulting unsaturated products then catalytically polymerized, or they can be polymerized by thermal processes involving decomposition as well as polymerization. Propane is not readily handled by these methods applicable to butane, and ethane cannot be handled by either method. Substantial proportions of butane, moreover, can also be included in liquid motor fuels, to provide proper vapor pressure characteristics, whereas ethane and propane are not useful in this manner. In this aspect, our process provides for the recovery of a valuable liquid product from such saturated hydrocarbons, ethane and propane particularly, which hitherto have had little if any more than fuel value.

To the extent that liquid phase conditions are maintained in the region of catalyst contact, our process enjoys several further incidental advantages. High capacities per unit of given size are thus attained. The catalyst is thus subjected to more or less continuous washing. Heavier condensation products which resist desorption in vapor phase operation and which tend to limit the effect of the catalyst as a matter of displacement are thus removed. Such washing, in conjunction with the lower temperatures used, also appears to prolong the useful life of the phosphoric acid catalyst.

30 We claim:

1. In the catalytic condensation of low boiling hydrocarbons including saturates and unsaturates to produce normally liquid hydrocarbons of gasoline boiling range, the improvement which 35 comprises passing a mixture of such hydrocarbons consisting predominantly of C₄- hydrocarbons and containing a substantial portion of C₅ hydrocarbons in contact with a phosphoric acid catalyst at a temperature of about 200°-450° F. under a pressure upwards of about 500 lbs. per square inch, whereby substantial condensation of saturates and unsaturates is effected.

2. In the catalytic condensation of low boiling hydrocarbons including saturates and unsaturates to produce normally liquid hydrocarbons of gasoline boiling range, the improvement which 45 comprises passing a mixture of such hydrocarbons consisting predominantly of C₄- hydrocarbons and containing a substantial amount of C₅ hydrocarbons, said mixture of hydrocarbons further containing not less than about 40 mol percent. of ethane, propane and butanes and a substantial proportion but not more than about 25 mol percent. of normal butylene and isobutylene 50 in its total content of C₄- hydrocarbons, in contact with a phosphoric acid catalyst at a temperature of about 200°-450° F. under a pressure upwards of about 500 lbs. per square inch, whereby substantial condensation of saturates and unsaturates is effected.

3. In the catalytic condensation of low boiling hydrocarbons including saturates and unsaturates to produce normally liquid hydrocarbons of 65 gasoline boiling range, the improvement which comprises passing a mixture of such hydrocarbons consisting predominantly of C₄- hydrocarbons and containing a substantial proportion but not more than about 25 mol percent. of C₅ hydrocarbons on its total content of C₄- hydrocarbons in contact with a phosphoric acid catalyst at a temperature of about 200°-450° F. under a pressure upwards of about 500 lbs. per square inch, whereby substantial condensation of saturates 70 and unsaturates is effected.

4. In the catalytic condensation of low boiling hydrocarbons including saturates and unsaturates to produce normally liquid hydrocarbons of gasoline boiling range, the improvement which 75 comprises passing a mixture of such hydrocarbons consisting predominantly of C₄- hydrocarbons and containing a substantial proportion but not more than about 25 mol percent. of C₅ hydrocarbons on its total content of C₄- hydrocarbons, said mixture of hydrocarbons further containing not less than about 40 mol percent. of ethane, propane and butanes and a substantial proportion but not more than about 25 mol percent. of normal butylene and isobutylene on its total content of C₄- hydrocarbons, 10 in contact with a phosphoric acid catalyst at a temperature of about 200°-450° F. under a pressure upwards of about 500 lbs. per square inch, whereby substantial condensation of saturates and unsaturates is effected.

5. In the catalytic condensation of low boiling hydrocarbons including saturates and unsaturates to produce normally liquid hydrocarbons of gasoline boiling range, the improvement which 15 comprises passing a mixture of such hydrocarbons consisting predominantly of C₄- hydrocarbons and containing a substantial proportion of C₅ hydrocarbons, said mixture of hydrocarbons further containing not less than about 40 mol percent. of ethane, propane and butanes, not less than about 15 mol percent. of ethane and propane and a substantial proportion but not more than about 25 mol percent. of normal butylene and isobutylene on its total content of C₄- hydrocarbons, 20 in contact with a phosphoric acid catalyst at a temperature of about 200°-450° F. under a pressure upwards of about 500 lbs. per square inch, whereby substantial condensation of saturates and unsaturates is effected.

6. In the catalytic condensation of low boiling hydrocarbons including saturates and unsaturates to produce normally liquid hydrocarbons of gasoline boiling range, the improvement which 25 comprises passing a mixture of such hydrocarbons consisting predominantly of C₄- hydrocarbons and containing a substantial proportion of C₅ hydrocarbons, said mixture of hydrocarbons further containing not less than about 40 mol percent. of ethane, propane and butanes and a substantial proportion but not more than about 40 mol percent. of ethylene, propylene and butylenes on its total content of C₄- hydrocarbons, 30 in contact with a phosphoric acid catalyst at a temperature of about 200°-450° F. under a pressure upwards of about 500 lbs. per square inch, 35 whereby substantial condensation of saturates and unsaturates is effected.

7. In the catalytic condensation of low boiling hydrocarbons including saturates and unsaturates to produce normally liquid hydrocarbons of gasoline boiling range, the improvement which 45 comprises passing a mixture of such hydrocarbons consisting predominantly of C₄- hydrocarbons and containing a substantial proportion of C₅ hydrocarbons, said mixture of hydrocarbons further containing not less than about 40 mol percent. of ethane, propane, and butanes, not less than about 15 mol percent. of ethane and propane, a substantial proportion but not more than about 35 mol percent. of ethylene, propylene and butylenes, and not more than about 25 mol percent. of normal butylene and isobutylene on its total content of C₄- hydrocarbons, 50 in contact with a phosphoric acid catalyst at a temperature of about 200°-450° F. under a pressure 55 upwards of about 500 lbs. per square inch, whereby substantial condensation of saturates and unsaturates is effected.

upwards of about 500 lbs. per square inch, whereby substantial condensation of saturates and unsaturates is effected.

8. In the catalytic condensation of low boiling hydrocarbons including saturates and unsaturates to produce normally liquid hydrocarbons of gasoline boiling range, the improvement which comprises passing a mixture of such hydrocarbons consisting predominantly of C_4 - hydrocarbons and containing a substantial portion of C_5 hydrocarbons in contact with a phosphoric acid catalyst at a temperature of about 200°-360° F. under a pressure upwards of about 700 lbs. per square inch, whereby substantial condensation of saturates and unsaturates is effected.

9. In the catalytic condensation of low boiling hydrocarbons including saturates and unsaturates to produce normally liquid hydrocarbons of gasoline boiling range, the improvement which comprises passing a mixture of such hydrocarbons consisting predominantly of C_4 - hydrocarbons and containing a substantial amount of C_5 hydrocarbons, said mixture of hydrocarbons further containing not less than about 40 mol percent. of ethane, propane and butanes and a substantial proportion but not more than about 25 mol percent. of normal butylene and isobutylene on its total content of C_4 - hydrocarbons, in contact with a phosphoric acid catalyst at a temperature of about 200°-360° F. under a pressure upwards of about 700 lbs. per square inch, whereby substantial condensation of saturates and unsaturates is effected.

10. In the catalytic condensation of low boiling hydrocarbons including saturates and unsat-

urates to produce normally liquid hydrocarbons of gasoline boiling range, the improvement which comprises passing a mixture of such hydrocarbons consisting predominantly of C_4 - hydrocarbons and containing a substantial proportion but not more than about 25 mol percent. of C_5 hydrocarbons on its total content of C_5 - hydrocarbons in contact with a phosphoric acid catalyst at a temperature of about 200°-360° F. under a pressure upwards of about 700 lbs. per square inch, whereby substantial condensation of saturates and unsaturates is effected.

11. In the catalytic condensation of low boiling hydrocarbons including saturates and unsaturates to produce normally liquid hydrocarbons of gasoline boiling range, the improvement which comprises passing a mixture of such hydrocarbons consisting predominantly of C_4 - hydrocarbons and containing a substantial proportion but not more than about 25 mol percent. of C_5 hydrocarbons on its total content of C_5 - hydrocarbons, said mixture of hydrocarbons further containing not less than about 40 mol percent. of ethane, propane and butanes and a substantial proportion but not more than about 25 mol per cent. of normal butylene and isobutylene on its total content of C_4 - hydrocarbons, in contact with a phosphoric acid catalyst at a temperature of about 200°-360° F. under a pressure upwards of about 700 lbs. per square inch, whereby substantial condensation of saturates and unsaturates is effected.
